US00D998687S

(12) **United States Design Patent** (10) **Patent No.:** **US D998,687 S**
Zheng et al. (45) **Date of Patent:** **** Sep. 12, 2023**

(54) **SMART GLASSES**

(71) Applicant: **Falcon Innovations Technology (Shenzhen) Co., Ltd**, Shenzhen (CN)

(72) Inventors: **Bin Zheng**, Shenzhen (CN); **Mingjie Wang**, Shenzhen (CN)

(73) Assignee: **Falcon Innovations Technology (Shenzhen) Co., Ltd**, Shenzhen (CN)

(**) Term: **15 Years**

(21) Appl. No.: **35/515,280**

(22) Filed: **Sep. 19, 2022**

(80) **Hague Agreement Data**

Int. Filing Date: **Sep. 19, 2022**

Int. Reg. No.: **DM/223681**

Int. Reg. Date: **Sep. 19, 2022**

Int. Reg. Pub. Date: **Oct. 7, 2022**

(30) **Foreign Application Priority Data**

Aug. 18, 2022 (CN) 202230541179.7

CLAIM

The ornamental design for a smart glasses, as shown and described.

DESCRIPTION

1. Smart glasses
- 1.1 : Front
- 1.2 : Back
- 1.3 : Left
- 1.4 : Right
- 1.5 : Top
- 1.6 : Bottom
- 1.7 : Perspective
- 1.8 : Perspective
- 1.9 : Perspective
- 1.10 : Perspective

The design is smart glasses used for augmented reality technology; figs. 1.1-1.10 are drawings showing an embodiment of the smart glasses.

1 Claim, 10 Drawing Sheets
